Des. 180,550
Patented July 2, 1957

180,550

COMBINED SOFA BED AND DESK

Louis Elliott Frey, Los Angeles, Calif.

Application June 27, 1955, Serial No. 36,691

Term of patent 14 years

(Cl. D15—11)

FIG. 1.

FIG. 3.

FIG. 4.

FIG. 5.

FIG. 6.

Fig. 1 is a front perspective view of a combined sofa bed and desk embodying my new design;

Fig. 2 is a similar view showing the same with the bed in open position;

Fig. 3 is a front elevational view of a combined sofa bed and desk embodying my new design, with the bed in closed position;

Fig. 4 is a rear elevational view of the same;

Fig. 5 is a top view of the same; and

Fig. 6 is an end view of the same, taken from the desk end.

I claim:

The ornamental design for a combined sofa bed and desk, substantially as shown and described.
